UNITED STATES PATENT OFFICE.

HENRY L. BROWN, OF PATERSON, NEW JERSEY, ASSIGNOR TO BROWN SPIN-WRIGHT COMPANY, OF NEW YORK, N. Y., A CORPORATION OF NEW YORK.

POWER-TRANSMITTING MECHANISM.

1,149,717.

Specification of Letters Patent. Patented Aug. 10, 1915.

Application filed January 6, 1910. Serial No. 536,681.

To all whom it may concern:

Be it known that I, HENRY L. BROWN, of Paterson, New Jersey, have invented certain Improvements in Power-Transmitting Mechanism, of which the following description, in connection with the accompanying drawings, is a specification, like letters on the drawings designating like parts.

This invention relates to power-transmitting mechanism and is of particular utility when embodied in apparatus for spinning or similar treatment of fibers, filaments or fibrous materials such as spinning frames for cotton, flax, silk and wool, although I contemplate the use of my invention in any field for which it is adapted by the nature of my improvements.

An important object of my invention is to provide means for gearing a metal driving band with a gear wheel the teeth of which are constituted by relatively short portions of helical threads such as are found in the ordinary feed-screw used in lathes, since such screws can be made with a minimum of expense and maximum accuracy owing to the proficiency of the manufacturers of such feed-screws, the excellent machinery available therefor, and the extended demand which makes the feed-screws a staple product. Accordingly, I have devised a band which may, and preferably will be a relatively thin and flexible strip of metal, and preferably flat throughout its length to reduce to a minimum all sources of friction and accidental engagement with extraneous objects, following in this respect the preferred form of driving band disclosed in my Letters Patent No. 957,650, granted May 10, 1910, but with this difference, viz., that by my present invention the band drive can be employed for the positive actuation of a regular gear wheel, in contradistinction to a special form of sprocket-wheel as in the form of my invention disclosed in the aforementioned patent, a form completely successful in its own wide field and by which was made possible for the first time the positive actuation of the spindles in a spinning frame by a metal band.

In carrying my invention into effect, I prefer to form the rotatable member or gear wheels of my improved power-transmitting mechanism by cutting short sections from a cylindrical feed-screw having, say, three

peripheral threads of suitable pitch and cross-section, 120° apart, circumferentially, and dressing the lateral faces of the pinions thus formed so that the ends of the helical teeth are terminated by surfaces parallel with the plane of rotation of the pinion and leaving such a lateral margin of the annular hub portion of the pinion that when two pinions are assembled co-axially, the adjacent ends of the threads on the pinions will be held apart by a substantial space. Each pinion, so constructed, will comprise three helical teeth bodily inclined laterally fore-and-aft relatively to the plane of rotation, and preferably the three teeth will together completely embrace the 360° of periphery for the sake of smooth continuity in operation, although I do not limit myself to the use of teeth subtending any specific circumferential arc, nor of any specific pitch, or number, except as found necessary for the particular installation in any given case. So also the number of pinions, or equivalent gears, and their arrangement, is immaterial, and may be varied to suit diverse contingencies, as for example in providing spindles for a spinning frame with gears, two helical pinions may be secured to the periphery of the spindle with their teeth oppositely inclined, to avoid undue thrust co-axially by reason of the inclination of drive surfaces laterally fore-and-aft of the direction of actuating engagement of the band and helical teeth; also the separation of the teeth of the two pinions by the width of the hub margins, as hereinbefore suggested, and the staggered arrangement of the teeth on one pinion opposite the spaces between teeth on the other will make possible the use of a band having a substantially continuous medial web lengthwise, between the band apertures which receive the teeth, thus strengthening the band greatly, and also promoting smoothness of operation by reason of the total absence of sharp points in the band, which is constantly being flexed as it runs around the pulleys, and would deteriorate under the bending stress on such points. These band apertures may be substantially straight, inclined bodily across the direction of movement of the band, and with parallel drive walls, and will preferably have end extensions substantially parallel with the direction of movement, in

order to afford clearance for the ends of the helical teeth even after the drive walls of the band apertures shall have become worn by actuating engagement with the helical teeth, and this feature of my invention I regard as applicable to any form of lengthwise acting member in which it may be embodied, the separation and staggered relation of the teeth in a herringbone gear being 10 a cognate feature of generic novelty and utility.

Another important object of my invention is the provision of an improved sprocket wheel of the type having peripheral actuating pins or studs, my improvements being directed toward the adaptation of this type for use with a flat metal band run substantially tangent to the periphery of a studded sprocket wheel of small diameter. The earlier forms of such sprockets being wholly incapable of use with such a band, owing to the entire absence heretofore of any provision to insure progressive continuity of positive actuation with rotating 20 members of such small diameter as the whirl of a spindle. In carrying into effect this portion of my invention, I make the studs movable radially, mounting them preferably in peripheral sockets, and arranging them so that under the action of centrifugal force they are protruded radially, and pressed into the apertures of a band suitably constructed to receive the studs, of which there are preferably two 30 or more parallel peripheral series in staggered relation to increase the number of points of actuating contact and thus maintain the continuity of action. This may be furthered also by forming the outer extremities of the studs with rounded contour, and the studs may have body slots with retaining pins transfixing them, to limit the outward play of the studs under the centrifugal action, but not interfering 40 with inward movement of the studs, which retire into their sockets if their sprocket stops, while the band continues to pass.

Among other noteworthy objects of my invention is the provision of a novel coupler 50 to permit the connection of spindles and their actuating whisks for co-rotation at times, and their disengagement at will without interfering with continued rotation of the whirl, special attention being paid to the frictional initiation of rotation of the spindle, preparatory to subsequent automatic coupling for positive co-rotation when the speed of the spindle approximates that of the whirl sufficiently to avoid shock, 55 for which purpose I may provide somewhat flexible irregularly spaced prongs on one member to enter corresponding pits in the other member after the preliminary frictional engagement of the prongs with 60 a suitable face part.

Still other objects include the provision of a bolster capable of receiving different types of actuating whirl and spindle; permitting considerable co-axial displacement therebetween; also a novel oil-bearing for 70 shell-spindles.

The various features of my invention will be illustrated and described fully in the accompanying drawings and specification and set forth in the claims.

In the drawings, Figure 1 illustrates in vertical section a spindle and spindle rail in the construction of which my improvements have been embodied, showing also in somewhat diagrammatic form the system for 80 the circulation of oil in accordance with my invention; Fig. 2 is a view in side elevation of a spindle shell like that shown in Fig. 1, but with a slightly modified form of supporting post, the parts being shown ready 85 for assembly; Fig. 3 is a plan view, looking from bottom to top of the spindle proper illustrated in Fig. 1, separate from the rail; Fig. 4 shows in front elevation a fragment of the driving band, in the construction of 90 which my invention has been embodied, the same being shown in engagement with a sprocket wheel taken separately from a spindle; Fig. 5 is a plan view on a smaller scale of an endless metallic band with pulleys and motor indicated diagrammatically, and a considerable number of spindles as 95 they would be found in a spinning frame along one rail, and in a spinning and twisting frame along the other rail; Fig. 6 is a 100 view in side elevation, illustrating a modified form of spindle and sprocket wheel; part of this figure being broken away to reveal interior construction, the coupler also being shown; Fig. 7 is a fragmentary 105 view in front elevation of the band for the sprocket-wheel shown in Fig. 6; Fig. 8 is a plan view looking from top to bottom of the sprocket wheel of Fig. 6, taken separately, and showing the coupling recesses; 110 Fig. 9 is a view in side elevation, similar to Fig. 6, illustrating a modified form of spindle and spindle-gear; part of this figure being broken away to reveal interior construction, the coupler also being shown.

In the embodiment of my invention selected for illustration and description to enable ready and complete understanding of my improvements, the part designated by the numeral 1 is a power transmitting member, which may be the driving or driven member in power transmitting apparatus where it is employed, and in the instance illustrated may be considered as the driving band for a series of spindles in a spinning frame, substantially as indicated on a reduced scale in Fig. 5, wherein the spindles bear respectively the numeral 2, while the numerals 3 and 4 designate respectively a suitable driving pulley, and the driving 125 130

pins or teeth with which it may be provided, and 5 is an electric motor connected by a belt 6 to a pulley 7 mounted on a shaft 8 which actuates the driving pulley 3, 5 the numeral 9 designating an idle pulley around which the other loop of the endless belt may run. The pulleys, motor power and other parts may be of any suitable and convenient construction and considerable 10 variation may be had in the construction of the driving band, which in accordance with my invention is provided with means to be engaged positively with a rotatable member for the progressive actuation of one of said 15 members by the other member, and as one convenient form of such means I prefer to provide the band with driving surfaces 10 inclined laterally fore-and-aft relatively to the length of said band, and these surfaces 20 may conveniently be formed in the manner illustrated, as the walls of apertures through the band, the latter being of any suitable material, such as a flat endless ribbon of steel, secured suitably at the joint, as by 25 welding or brazing. The contour of these apertures may vary in accordance with the requirements of particular installations, and for many purposes the form illustrated in Figs. 1 to 5 will be found most convenient, 30 these apertures being such as to receive and coöperate with the threads of screw or spiral worm, gear or sprocket wheels such as that shown at 20, best seen in Figs. 1, 2 and 4, the numeral 21 designating the threads or 35 teeth of the sprocket wheel, the same being shown in Fig. 4 in position engaged with the band, entering the apertures thereof and coöperating or in a position to coöperate with the walls 10 thereof. The numeral 30 40 designates a similar sprocket wheel provided with teeth 31 of spiral form similar to those shown at 21, but of opposite pitch, and arranged in staggered relation thereto, so that the end of each tooth on one of the 45 wheels comes opposite the space between two of the teeth on the other wheel, the teeth 21 being preferably somewhat removed from the ends of the teeth 31, suitable means being provided to maintain the wheels in 50 this relation, and to support them in position upon the device with which they are to rotate. As a convenient form of such means I have shown a hub or sleeve 40 upon which the wheels may be secured in suitable fashion, as by shrinking, with set screws 22, 32 either or both, or as found suitable in accordance with the exigencies of particular installations. The band apertures are best 55 seen in Fig. 4, where they are arranged in double lines diverging from the middle of the band, along which is preferably left a continuous web 12, for the sake of strength, and to avoid sharp points, which might be detrimental to smoothness of operation if 60 the apertures on opposite sides were in com-

munication at their adjacent ends. This form of band may be run in either direction, with equal facility, and may be the driving or driven member. I prefer to have the double series of apertures, oppositely inclined, but it is not essential to my invention to have such a plurality of rows of inclined surfaces 10, the double arrangement serving advantageously, however, to balance the coaxial thrust upon the band due to the inclination of the surfaces 10 engaging with the inclined surfaces of the teeth 21, 31. The apertures will be of sufficient length to give ample clearance for entry and exit of the screw teeth 21, 31, and may be somewhat 70 elongated as indicated at 25, 35, so that when the walls 10 become worn, the clearance will 75 still be sufficient.

The coöperating band and gear above described constitute a driving couple forming 80 the subject of generic claims in my copending application Serial No. 675,403, filed February 5, 1912, the same having been divided from my present application.

My improved metallic band drive may be 85 used to drive spindles of the types now in use, such as that illustrated in Fig. 6, and designated by the reference numeral 301, the spindle there shown being of a type well known in silk-spinning, having a tapered 90 upper blade to receive the bobbin 302 which is maintained in place by a collar 303, the latter being separately formed or integral with the spindle, as found most convenient in the particular installation, this form of 95 spindle being usually tapered also toward its foot 304 where it enters a suitable bolster or supporting member 305 the body 306 of which may be threaded, and a flange 307 provided, to facilitate its firm attachment 100 in adjusted position upon a suitable "rail" (not shown). Preferably when such a bolster is used, it will be constructed with an upwardly extending neck or bearing portion 308, shown in Fig. 6, to serve as a bearing for a sprocket-wheel-hub 309, the latter constituting one convenient form of rotatable member, to be engaged peripherally 105 with a driving band of suitable form, and to be coupled with the spindle for rotation of the latter, the hub 309 preferably being of annular form with an axial bore 310 best seen in Fig. 8 (on a somewhat smaller scale) 110 to receive the neck 308 and be seated snugly for rotation thereupon. The hub 309 may 115 have actuating projections of the spiral type illustrated in Figs. 2 and 9, or of any suitable type, the type shown in Fig. 6 being one convenient form of construction, comprising 120 a double series of actuating studs 312 mounted to move radially in recesses or sockets 313, suitable means being provided to limit the movement of the studs in the slots, and their projection beyond the periphery of the hub 309. For this purpose I have shown 125

pins 314 passing through the material of the hub from its flat faces, and entering slots 315 in the shanks of the studs, the pins being in their turn held in place by suitable means preferably, such as the face-plates 316, fastened by screws 317 (see Fig. 8), the face-plates being preferably annular, with a central aperture of a size suitable to admit a bushing or extension 318 which may be formed integrally with the material of the hub, or separately therefrom, preferably extending beyond each face of the hub when a face-plate is provided at each end.

The studs 312 are shown at their outer positions in the lower series of Fig. 6, and at their inner position in the upper series, for clearness of illustration, but usually all the studs will be extended when the hub is in operation, under the action of centrifugal force, the extremities of the studs being preferably rounded as indicated, to facilitate the progressive entrance of the studs respectively within the apertures of a suitable band, such as the metal band 319, shown in Fig. 7, having a plurality of series 320 and 321, of apertures, staggered to facilitate continuous engagement of the band with the sprocket wheel studs. The movable arrangement of the studs 312 facilitates prompt entrance into the band apertures 319 and 320 by reason of the steady centrifugal pressure, and if for any reason the hub 309 is stopped, the studs retire into their sockets under the action of the band, allowing the latter to pass freely past the studs.

In order to permit withdrawal of the spindle when desired, without disturbing the hub 309, which may be left in its position of engagement with the band 319, rotating freely under the action thereof, I have devised a form of coupling which is of general utility in its adaptation to various types of spindles and their whirls, including the types shown in Figs. 2, 6 and 9. A simple form of this coupling device comprises somewhat flexible prongs 401 upon one of the rotatable members constructed so as to enter pits or recesses 402 in the other member, the prongs being on the spindle in the instance illustrated, and consisting of wires about an inch long extending through the collar 303; while the pits 402 are formed in the upper face-plate 316 of the sprocket-wheel, and in the face of the sprocket wheel itself, as best seen in Fig. 6, where a portion of the periphery of the hub, etc., is broken away to reveal the free end of one of the prongs 401 in engagement with the wall at the far side of the recess 402. Preferably the pits 402 will be deep enough, and the prongs 401 will be long enough, to permit some coaxial play of one relatively to the other without disconnection, as both the spindle and the sprocket-wheel are liable to such occasional co-axial displacements. The number

and location of the pits and prongs may vary according to the requirements of particular installations, and I have found it advantageous to arrange them at somewhat uneven distances around the face of the hub, 70 so that when the spindle is dropped into the aperture 310 the prongs 401 will not enter the pits 302 immediately, but will be engaged with the face-plate 316, and the friction between the prongs and face-plate 75 will cause the prongs and their spindle to rotate, with the face-plate, but at a lower speed, until the speed of the spindle approximates that of the sprocket wheel, when the prongs will drop into the pits, and the 80 sprocket wheel will actuate the prongs and their spindle at the same rotative speed of the sprocket wheel as long as the connection continues. The prongs 401 may, and preferably will, be made of flexible wire, so that 85 there will be little shock to the apparatus when the spindle is dropped on the rapidly rotating sprocket wheel. The prongs are shown as straight, but may be of any suitable contour, and may be set directly in the 90 spindle blade instead of in a collar thereof. The face-plate 316 may be of hardened metal to withstand the frictional wear of the prongs. I have not claimed this coupling arrangement specifically in my present application, as the same forms the subject of claims in my copending application, Serial No. 594,960, divided from this application and filed November 30, 1910. 95

I have shown in Fig. 1 a form of spindle 100 described more at length in my Letters Patent No. 987,546, granted March 21, 1911, to which reference may be had, and accordingly it will suffice for the purposes of my present application to describe very briefly 105 the general features of this spindle, in which the lower part a^3 of the rotatable shell a is the equivalent of the hub member 40 in Fig. 2, already described, and on which the whirls 20, 30, are mounted, with their helical teeth 21, 31, in position to be driven by the metal band 1. Preferably a suitable means will be provided to hold the band 1 up to its work, as for example guide-posts, such as that shown at a^{50} screwed into the 110 rail b at suitable intervals. The blade of the spindle a^1 is shown as provided with a bobbin I , and a^2 designates a supporting post extending upward axially within the socket of the shell a and provided with a bearing sphere a^4 and a bearing bushing a^5 to be engaged snugly with the shell, the sphere having an axial bore a^6 to pass the post so that the sphere may rotate freely between the post and the shell, the bearing surfaces at 115 this region being indicated by the reference characters a^7 , a^8 . The member a^9 is a bushing having a bearing surface a^{10} which is engaged with the lower surface of the sphere a^4 , and this bushing has an axial bore a^{11} 120

125

130

to pass the post a^2 and is secured adjustably within the mouth of the shell by a threaded joint a^{12} , screws a^{13} being shown to fasten it in adjusted position, for which purpose the 5 heads of the screws enter recesses a^{14} in the shell, best seen in Fig. 3. A spring a^{15} is shown, to hold the bushing a^5 snugly up against a bearing surface a^{16} in the shell, and the shoulder a^{17} of the post a^2 serves 10 as an abutment for the spring while a washer a^{18} is shown as interposed between the spring and the part a^{19} of the bush a^5 , the latter rotating freely between the shell surface a^{16} and a wear sleeve a^{20} held in place 15 by the swaged over tip a^{21} of the post a^2 . The supporting post a^2 is provided with a channel f through which a suitable lubricant, as oil, may be introduced to the upper bearing a^6 and lower bearing a^4 ; also to the 20 teeth 21, 31 through ports f^1 , the excess of oil collecting in the container B to such a height as may be found suitable, as for example that indicated at b^4 , whence it may be withdrawn by a pipe f^2 and forced by a 25 pump f^3 through a pipe f^4 to an overhead tank F, passing thence by a supply pipe f^5 to the channel f of the post a^2 to which the coupling f^{50} furnishes a connection, so that recurrent circulation of oil may be maintained. 30

The parts above designated are, and preferably will be, in general as described and claimed in my aforesaid Patent No. 987,546, but may vary to suit the varying requirements of diverse installations. The reference characters a^{24} — a^{30} designate one such modification also described in my said patent.

In accordance with an important feature 40 of my invention, I provide means to maintain a sufficient upward pressure on the oil in the channel f to sustain the weight of the spindle, bobbin, etc., on an oil film F^2 , constituting an oil bearing between the upper 45 surface of the post a^2 and the surface of the shell socket there above, and in order to insure this pressure by positive means, I have shown the tank F as provided with a closure F^1 , so that the desired pressure may be maintained in the pipes f^4 , f^5 , f , by the pump f^3 . 50

The spindles indicated at 2 in Fig. 5 may be mounted on any suitable "rail," by which term I designate broadly their support, without any technical limitation, and 55 a suitable form of rail is shown at b, in Fig. 1, the spindle a^2 being secured thereto by nuts b^1 and the rail being shown as secured adjustably by bolts b^2 passing through slots into brackets b^3 fastened to the side walls of

the container B. The container may have 60 a cover as at D.

Having described my invention thus fully and suitable means by which the same may be carried into effect, I wish it to be understood that I do not limit myself to the specific materials and structural details selected for illustration and description herein, nor in general otherwise than as set forth in the claims read in connection with this specification. 65

What I claim and desire to secure by Letters Patent is:

1. A spinning spindle, having a plurality of oppositely inclined, helical, peripheral teeth thereupon, in staggered relation to 75 each other, and separated co-axially; substantially as described.

2. The combination with a spinning spindle having a part constituting a hub; of a plurality of annuli each having peripheral, 80 helical teeth, the inclination of said teeth being opposed on neighboring annuli, said annuli being mounted on said hub part.

3. A shell-spindle; an axial support therewithin; a universal bearing on said support 85 within said shell and on which said spindle rotates; and a helical gear surrounding the periphery of said shell at the region of said universal bearing, said gear comprising a plurality of series of helical teeth, the series 90 being separated from each other, and one series containing teeth of opposed inclination to the teeth of said other series, and arranged in staggered relation thereto; substantially as described. 95

4. The combination with a spinning device having a member provided with helical driving teeth, of a driving band geared to said teeth, said band having apertures entered by said teeth. 100

5. A spinning member having helical teeth to be engaged actuating with an apertured driving band, said helical teeth being constructed and arranged to enter the apertures of said band. 105

6. Spinning apparatus; comprising a plurality of spindles having respectively members provided with helical driving teeth; and a driving band having individual driving surfaces geared to said teeth. 110

Signed at New York in the county and State of New York this 21st day of December, 1909.
